THREADING-DIE HOLDER

Frederick H. Warren, Waterbury, Conn., assignor
to Greenfield Tap and Die Corporation, Green-
field, Mass., a corporation of Massachusetts

Application March 8, 1946, Serial No. 653,222

2 Claims. (Cl. 10—119)

1

This invention relates to improvements in threading-die holders for holding threading-dies of the type having a plurality of integral forwardly-extending flexible threading-prongs, commonly referred to as the "acorn" type.

Heretofore in threading-die holders for acorn threading-dies, the screw-threaded adjusting-sleeve for adjusting the threading-prongs of the threading-die has been engaged in threaded relation with the head of the threading-die holder, so that when the adjusting-sleeve is rotated in the proper direction, it results in the adjusting-sleeve rotating and moving longitudinally at the same time to bring about the flexing adjustment of the threading-prongs, with the consequence that the friction of the rotary sliding action of the adjusting-sleeve on the threading-prongs, flexes the threading-prongs sidewise so that the helix angle of the thread-cutting teeth of the threading-prongs is altered, so that the teeth cut a distorted form of thread, inasmuch as the trailing edges of the cutting-teeth do not track properly with the advanced edges of their respective cutting-teeth, thus decreasing the accuracy of the lead or pitch of the thread that is cut on an article to be threaded. This distortion also brings about another serious defect when the threading-die is being employed for cutting a straight thread, in that the distortion of the threading-prongs results in cutting a thread having a substantial taper instead of being truly straight.

One object of the present invention, therefore, is to provide an improved threading-die holder which will have a true radial adjusting action without any sidewise or circumferential distorting action.

With the above and other objects in view, as will appear to those skilled in the art from the present disclosure, this invention includes all features in the said disclosure which are novel over the prior art.

In the description and claims, the various parts and steps are identified by specific terms for convenience, but they are intended to be as generic in their application as the prior art will permit.

In the accompanying drawings forming part of the present disclosure, in which one way of carrying out the invention is shown for illustrative purposes:

Fig. 1 is a side elevation illustrating one embodiment made in accordance with the present invention;

Fig. 2 is a right-end elevation of Fig. 1;

Fig. 3 is a left-end elevation of Fig. 1;

2

Fig. 4 is a longitudinal vertical central sectional view on line 4—4 of Fig. 2;

Fig. 5 is a transverse sectional view on line 5—5 of Fig. 4;

Fig. 6 is a transverse sectional view on line 6—6 of Fig. 4;

Fig. 7 is a fragmental perspective view partly in section, of the body including the shank and head;

Fig. 8 is a fragmental perspective view of the operating-collar;

Fig. 9 is a fragmental perspective view of the locking-collar;

Fig. 10 is a perspective view of an acorn threading-die; and

Fig. 11 is a fragmental perspective view of the adjusting-sleeve.

Referring to the drawings showing the particular form of the invention chosen for illustration therein, the threading-die holder 20 includes a body 21 which, in turn, includes a shank 22 and a head 23. The head 23 has a stem 24 slidable in the cylindrical bore 25 of the shank 22, which stem 24 has a bushing 26 secured thereon by a screw 27. The bushing 26 is slidable in the enlarged bore 28 of the body 22. A coil-spring 29 is engaged between the bushing 26 and the annular shoulder 30 so as to yieldingly hold the stem 24 in the position illustrated in Fig. 4, for permitting it to move longitudinally to the right for a limited distance against the action of the spring 29.

The head 23 has rearwardly-extending coupling-extension means 31 in the form of a parallel-sided key at its rear end, which is longitudinally slidable in the coupling-recess means 32 at the forward end of the shank 22. The coupling-extension means 31 has its opposite ends extending beyond the circumference of the shank 22 and provided with interrupted thread-portions 33 and 34 adapted to threadedly receive the screw-threaded interior 35 of the locking-collar 36.

The head 23 has forwardly-extending coupling-extentions 37 and 38 in the form of pins extending forwardly into coupling-recesses 39 and 40 formed at the rear end of the threading-die 41. The threading-die 41 is of the well known "acorn" type having a plurality of integral forwardly-extending flexible threading-prongs or arms 42 each of which is provided with a plurality of thread-cutting teeth 43. Each prong 42 has a conical surface-portion 44 adapted to be engaged by a conical surface 45 of a die-adjusting sleeve 46 which has a cylindrical bore 47 having a neat sliding fit over the cylindrical

outer surface 48 of the head 23. A coupling-pin 49 extends radially inward beyond the cylindrical surface 47, to slidely engage the longitudinal slot 50 in the outer portion of the head 23 to guide the adjusting-sleeve longitudinally forwardly and rearwardly and prevent relative rotation between the parts 23 and 46.

The cup-shaped operating-collar 51 has a central aperture 52 through its rear or bottom wall 53 to permit the collar 51 to be slid over the shank 22 and threaded portions 33 and 34, to permit of bringing the bottom or rear wall 53 against the rear face 54 of the head 23. The operating-collar 51 has interior threads 55 threadedly engageable with the exterior threads 56 of the adjusting-sleeve 46.

Operation

In the complete device assembled in the relation illustrated in Figs. 1 and 4, and viewing it from the right end thereof, and assuming the locking-collar 36 to have been rotated clockwise to unscrew it and move it rearwardly to bring it spaced away from, and out of locking engagement with the operating-collar 51, if it is now desired to adjust the threading-prongs 42 by flexing or springing them radially inward, the operating-collar 51 is to be rotated counterclockwise, which will draw or pull the adjusting-sleeve 46 longitudinally rearwardly but not rotatably, due to the pin 49 sliding along in the longitudinal groove 50, to thus cause the conical surface 45 of the sleeve 46 to have a camming action upon the conical surface-portions 44 of the prongs 42, to thus spring the prongs radially inward for adjustment of the diameter of the thread to be cut. After the operating-collar 51 has been rotated sufficiently to bring about the desired degree of adjustment of the threading-prongs 42, the locking-collar 36 is to be rotated counterclockwise until it jams against the rear or end wall 53 of the operating-collar 51, to thus lock the operating-collar 51 against any rotational movement.

It will thus be seen that inasmuch as the adjusting-sleeve 46 moves only in a longitudinal direction while springing the prongs 42 inward, and does not have any rotational movement, there can be no circumferential or sidewise springing of the threading-prongs 42.

Thus applicant's improved threading-die holder avoids the defects of the prior art construction which owing to the circumferential or sidewise distortion of the threading-prongs, alters the helix angle to thus produce a thread of distorted form, in which the trailing edge of each cutting-tooth does not track properly with the advance edge of such cutting-tooth, and the altered helix angle objectionably affects the accuracy of the lead or pitch of the thread. Also, when it is desired to cut a straight thread, applicant's improved construction permits of obtaining much nearer to a true straight thread than is possible with the previously described prior art construction.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An adjustable threading-tool including in combination: a body having a shank and a head; said shank having a recess at its front end; said head being of greater diameter than the diameter of said shank and having a key at its rear end, which key extends into said recess and prevents relative rotation but permits relative longitudinal sliding movement between said shank and said head; said key having its opposite radial ends extending beyond said shank, and the opposite end-surfaces of said ends being provided with screw threads; a threading-die having an integral, annularly-continuous rear end-portion in relatively non-rotatable engagement with said head, and having a plurality of flexible threading-prongs integral with and extending forwardly from said rear end-portion; a die-adjusting sleeve surrounding said threading-die, and non-rotatably but longitudinally slidably engaging said head, and engageable with the forward end-portions of said threading-prongs to flex said prongs toward the axis of said threading-die when said die-adjusting sleeve is moved longitudinally rearwardly, and having an integral, annularly-continuous rear-portion provided with screw threads; an operating-collar having an integral, annularly-continuous forward-portion provided with screw threads in threaded engagement with the said screw threads of said die-adjusting sleeve, and having an apertured end-wall engageable with said head to limit the forward movement of said operating-collar relative to said head, rotation of said operating-collar in one direction causing said adjusting-sleeve to move longitudinally rearwardly, and rotation in the opposite direction permitting said adjusting-sleeve to move longitudinally forwardly; and a locking-collar threadedly engaged with the threads of said key-ends to lock said operating-collar against rotation relatively to said head.
2. An adjustable threading-tool including in combination: a body having a shank and a head; said shank having a recess at its front end; said head being of greater diameter than the diameter of said shank and having a key at its rear end, which key extends into said recess and prevents relative rotation but permits relative longitudinal sliding movement between said shank and said head; said key having its opposite radial ends extending beyond said shank, and the opposite end-surfaces of said ends being provided with screw threads; a threading-die having an integral, annularly-continuous rear end-portion in relatively non-rotatable engagement with said head, and having a plurality of flexible threading-prongs integral with and extending forwardly from said rear end-portion; a die-adjusting sleeve surrounding said threading-die; and non-rotatably but longitudinally slidably engaging said head, and engageable with the forward end-portions of said threading-prongs to flex said prongs toward the axis of said threading-die when said die-adjusting sleeve is moved longitudinally rearwardly, and having an integral, annularly-continuous rear-portion provided with screw threads; an operating-collar having an aperture therethrough and an integral, annularly-continuous forward-portion provided with screw threads in threaded engagement with the said screw threads of said die-adjusting sleeve, and having means engageable with said head to limit the forward movement of said operating-collar relative to said head, rotation of said operating-collar in one direction causing said adjusting-sleeve to

move longitudinally rearwardly, and rotation in the opposite direction permitting said adjusting-sleeve to move longitudinally forwardly; and a locking-collar threadedly engaged with the threads of said key-ends to lock said operating-collar against rotation relatively to said head.

FREDERICK H. WARREN.
